UNITED STATES PATENT OFFICE.

EDWIN A. FOSTER, OF BRATTLEBOROUGH, VERMONT, ASSIGNOR TO
J. ESTEY & CO., OF SAME PLACE.

REED-ORGAN.

SPECIFICATION forming part of Letters Patent No. 289,638, dated December 4, 1883.

Application filed June 19, 1883. (No model.)

To all whom it may concern:

Be it known that I, EDWIN A. FOSTER, a citizen of the United States, residing at Brattleborough, in the county of Windham and 5 State of Vermont, have invented certain Improvements in Reed-Organs, of which the following is a specification.

My invention relates to means for operating the exhausters of an organ, whereby either 10 the feet of the player may be employed in the usual way or the exhausters may be operated by a hand-lever.

Organs have before been provided with means for accomplishing this, consisting of a 15 double lever, or lever composed of two members or elements, each of which is connected to its particular exhauster. These elements stand crossed normally, but are brought together and coupled when it is desired to work 20 the exhausters by hand, whereupon they work together as one lever. My invention consists in certain improvements upon this mechanism, which will be fully set forth hereinafter.

In the drawings, which serve to illustrate 25 my invention, Figure 1 is a front elevation of the lower part of an organ, with the front of the casing removed to show the levers. Fig. 2 is a cross-section taken substantially on line 2 2 in Fig. 1. Fig. 3 is a longitudinal vertical section taken on line 3 3 in Fig. 2, and looking in the direction of the arrow. Fig. 4 is a view similar to Fig. 1, showing the levers coupled. Figs. 5, 6, and 7 are detached perspective views, showing the construction of 30 the levers.

Let A represent the frame of an organ, B the board upon which the exhausters are mounted, CC the exhausters, aa their springs, D D the pedals, and b b their straps, arranged 40 to pass over guide-pulleys c c. These parts may all be constructed in the usual way. Pressure of the foot upon either pedal actuates the exhauster connected with such pedal.

The means for blowing the organ by hand, 45 to which my invention relates, consist of levers E and E', arranged side by side and mounted on a common fulcrum, d, and each connected to one of the exhausters. One end of the lever E is connected by a strap, e, with

one exhauster, and the opposite end of the 50 lever E' is connected by a strap, e', to the other exhauster. The levers are so counterpoised that they stand normally crossed in the position shown in Figs. 1 and 3, their ends to which the straps are connected being uppermost, and the operation of the exhausters by 55 the pedals does not affect them.

In order to operate the bellows by hand, it is necessary to bring the two levers together, as shown in Fig. 4, and fasten or couple them 60 to each other, so that they shall act as one lever. This alone is not new with me, it being common to bring the two together, and then, by sliding one lever longitudinally on a slotted fulcrum, to cause a pin upon it to enter a 65 slot in the other lever; but this connection is unhandy, and the levers are apt to become disconnected by an accidental displacement of the sliding lever.

My invention consists in providing an automatic elastic catch or latch, which couples the levers at the first downstroke in pumping by hand, and which cannot be unintentionally disengaged. The particular construction of 70 this catch is not very important, it being only 75 essential that the levers shall automatically couple on being brought together, and that they shall be uncoupled by a manipulation of the handle which projects outside of the organ-case.

The catch device which I have designed is very simple, and utilizes in its operation the slight spring or elasticity of the levers. The handle F is removable, and is formed with a shank, g, Fig. 5, which fits into a socket, f, Fig. 85 7, on the end of the lever E. When the handle is thrust into this socket, as shown in Figs. 1 and 3, a beveled or wedge-shaped end, h, Fig. 5, on the handle projects beyond the socket; and when the handle is pressed down, carrying down the lever E, the beveled end i on the lever E', Fig. 6, is encountered by the portion 90 h, which wipes past it. The levers spring apart sufficiently to permit this, and when h has passed below i, as denoted by the dotted lines 95 in Fig. 3, the levers spring toward each other again and are coupled together, so that the continued reciprocation of the handle carries

both levers with it, and works the exhausters alternately as with one lever. The end *h* of the handle and the end *i* of the lever *E'* are kept pressed together by the tension of the 5 exhauster-springs, which tend to cause the levers to resume their crossed position. (Shown in Fig. 1.) When it is desired to uncouple the levers, it is only necessary to pull out the handle *F*, or even to pull it back so that its 10 end *h* shall pass from under the end *i* of the lever *E'*. The lever *E* is provided with a counter-weight, *j*, to keep the end to which the strap *e* is attached elevated. The other lever is similarly counterbalanced, so that the two 15 levers are kept from vibrating when the bellows are being worked by the feet.

I claim as my invention—

1. In a reed-organ, the combination, with the exhausters and foot-pedals, of two levers 20 arranged side by side, mounted both on the same fulcrum and each connected at one end to one of the exhausters, with an elastic catch

or latch, constructed substantially as set forth, adapted to automatically couple the two levers together when they are moved parallel 25 to each other, whereby they are caused to act as a single lever for working the exhausters by hand.

2. In a reed-organ, the combination, with the exhausters, of the lever *E*, provided with a socket, *f*, and connected to its exhauster by a strap, *e*, the lever *E'*, provided with a projection, *i*, and connected to its exhauster by a strap, *e'*, and the handle *F*, provided with a projection, *h*, the two levers having one fulcrum *d* in common, substantially as set forth. 35

In witness whereof I have hereunto signed my name in the presence of two subscribing witnesses.

EDWIN A. FOSTER.
